(57) **CLAIM**

The ornamental design for a safety debris collecting device for a hand held power tool, as shown and described.

DESCRIPTION

FIG. 1 is an exploded side elevation view of a safety debris collecting device for a hand held power tool showing my new design, the opposite side view being a mirror image of that shown;

FIG. 2 is a side elevation view thereof in an assembled condition;

FIG. 3 is a front elevational view thereof showing alternative position for storage in which all the elements are compressed and stored within the debris collecting container portion of the safety debris collecting device for a hand held power tool;

FIG. 4 is a bottom plan view of FIG. 2;

FIG. 5 is a top plan view of FIG. 2; and,

FIG. 6 is an enlarged view of circled region 6 of FIG. 1.
